UNITED STATES PATENT OFFICE.

OSCAR JOHNSON, OF SEATTLE, WASHINGTON.

ELECTRIC WATER-HEATER.

No. 887,331.

Specification of Letters Patent.

Patented May 12, 1908.

Application filed December 29, 1905. Serial No. 293,771.

To all whom it may concern:

Be it known that I, OSCAR JOHNSON, a citizen of the United States, and resident of the city of Seattle, in the county of King and State of Washington, have invented certain new and useful Improvements in Electric Water-Heaters, of which the following is a specification.

My invention relates to an improvement in electrical water heaters, and comprises the novel parts and combinations of parts hereinafter particularly pointed out in the claims.

The object of my invention is to improve and simplify such devices.

15 In the drawings I have shown my invention embodied in the form now preferred by me.

Figure 1 is a longitudinal section of my device. Fig. 2 is a plan view of the lower head 20 showing the water and electrical connections.

In the form of electrical water heaters which employ a wire or like device as the resistance medium, if the current is turned on before the wire is immersed in the liquid the 25 wire is liable to be burned out.

One object of my invention is to produce a heater in which there is no danger of burning out from such a cause. The means employed by me secures this result in two ways; 30 first by making the water the resistance medium; second, which is related to the first, by having the circuit normally broken and automatically closing it by the inflowing water.

As pole pieces I employ metal of such large 35 size that there is no danger of its burning out or being injured by any current which it is possible to use, and pass the water to be heated between them, the opposite pole pieces being normally insulated from each other 40 and the circuit being closed by the water between them.

The form of pole pieces preferred by me consists of a series of nested tubes, 2, 3, 4 and 5, as shown in Fig. 1. To hold these in place, 45 I employ heads 6 and 7 which are provided with grooves 16 adapted to receive the ends of the tubes. These tubes or pole pieces, where more than two or used, are grouped in pairs designed for connection with opposite 50 sides of an electrical circuit. The heads should insulate these tubes, or at least those of any pair.

The tubes of each pair constitute pole pieces for an open circuit which is closed by 55 the water which is passed between them. The water therefore acts as the resistance

medium and not the pole pieces. The latter are of such a size and conductive capacity that the current will not heat them directly. The heating is caused by the resistance of the 60 water.

The heads 6 and 7 are either of an insulating material or provided with means whereby the various tubes of each pair are insulated from each other. I have shown these 65 heads as made of glass and provided with packing rings or washers in the bottom of the grooves receiving the tube ends. I have also shown means for electrically connecting the tubes of all the pairs in two sets corresponding to positive and negative poles. The means shown consists of two wires 10, 10 embedded in the glass and connecting corresponding tubes of each pair. Binding posts 70 11 for the attachment of the supply wires are 75 connected, one to each group.

One of the heads, as the lower head 6, is provided with passages 12, through which water may pass from one set of tubes to the other. This head has a section which is 80 thicker than the remainder, bounded by the dotted line 9 of Fig. 2, in which is located the binding poles 11, and the connecting wires 10. A cap 8 outside of the head 6 fits over a shoulder on the head and forms a chamber 85 which connects the holes 12 which pass through the head, connecting with the annular spaces between the tubes of each pair. The space between the tubes 3 and 4 is designed as an insulating space and may contain only air, or any suitable insulating substance. The other head 7 should be insulating in the same way as the head 6, but has no water passages except to connect with the space between the tubes of the outer set, 4 90 and 5. The outer tube 5 is made longer than the others, and the head 7 fits within this and is provided with peripheral notches permitting free passage of the water.

The water supply pipe 1 passes through 100 both heads 6 and 7 and is threaded to receive clamping nuts 14, 15 which bind the whole together. Pipe 1 is provided with openings 24 for the escape of the water, and pipe 2 has similar openings 23 near one end. The head 105 8 is preferably covered by an insulating disk 20 and a finishing cap 21 of metal, and a packing washer 25 is placed beneath the nut 14. A packing washer 22 is also placed beneath the nut 15. The pipe 1 is stopped at 110 its upper end by a plug 26.

Secured to the upper projecting end of the

pipe 1 is an extension 27 having holes 28 through which water may flow from the receiving chamber 29. A cap 30, preferably of insulating material, as glass, covers the extended end of tube 5 and is held down by nut 33. A packing washer 31 and finishing cap 32 are also placed beneath this nut.

The discharge pipe 34 is connected with the tube 27. This pipe is preferably either 10 of an insulating material or is provided with an insulating lining. I have shown the latter construction consisting of an iron or brass pipe provided with a lining 35 of glass, porcelain, enamel or other insulating material.

15 Outside the whole I prefer to put a finishing jacket 36 and between this and the tube 5 a layer of material which has insulating properties against both heat and electricity, as asbestos.

20 In using my device the lower pipe 38 is connected with the water supply and the binding posts 11, 11 connected with a source of electro motive force. The order of making this connection is immaterial as the circuit 25 remains open until water has connected the poles and the energy of the current is operative to produce heat only upon the water. This heater may be used upon currents of different voltages and also upon either direct 30 or alternating currents.

Having thus described my invention, what I claim and desire to secure by Letters Patent is:

1. An electrical liquid heater having a series 35 of nested tubes grouped in pairs, means connecting the annular spaces between the tubes of the pairs to constitute a liquid conducting passage, and means for forming opposite electrical connections with the respective tubes of the pairs.

2. An electrical liquid heater having a series 40 of nested tubes grouped in pairs of successive tubes, the spaces between the tubes of the pairs constituting liquid conducting passages, and the spaces between the pairs constituting insulation.

3. An electrical liquid heater having a series 45 of nested tubes grouped in pairs, means for supplying liquid to the annular space between the tubes of the pair at one end of the series, means for conducting liquid from the annular spaces between the tubes of the pair at the other end of the series, means for connecting the spaces between the tubes of the 50 different pairs to form a continuous water conducting passage, and means for connecting the tubes of the pairs respectively to opposite sides of an electrical circuit.

4. An electrical liquid heater having a plurality 55 of pairs of tubes nested within each other to form annular spaces between successive tubes, each tube being insulated from its adjoining tubes, means for connecting the spaces between the tubes of the different 60 pairs in series, water supply and discharge

connections with said spaces at opposite ends of the series, and means for connecting opposite phases of an electrical current with the respective tubes of the pairs.

5. An electrical liquid heater having a plurality 65 of pairs of tubes nested within each other to form annular spaces, insulating heads for said tubes provided with liquid conducting passages adapted to connect the spaces between the tubes of the different 70 pairs, and means for connecting the corresponding tubes of each pair with its respective side of an open circuit.

6. An electrical liquid heater having nested 75 tubes, insulating heads having grooves 80 for receiving said tubes and supporting them apart from each other, one of said heads having passages permitting flow of liquid from the space between one pair of the tubes to the space between another pair of tubes, and 85 means for connecting the tubes of each pair to constitute opposite pole pieces of an open circuit.

7. An electrical liquid heater having nested 90 tubes grouped in pairs, insulating heads 95 for the ends of the tubes supporting them apart from each other, liquid conducting means connecting the annular spaces between the tubes of the different pairs to form a continuous passage thereof, a liquid supply 100 tube extending through and projecting from both heads and the innermost of the other tubes and provided with means for clamping said heads upon the other tubes, said supply tube and the innermost of the other tubes 105 having connecting liquid passages, said supply tube being plugged near one head; the outermost of the nested tubes projecting beyond this head, a cap covering this tube and forming a discharge chamber which is connected with the liquid passage of the outermost pair of tubes, the central supply and clamping tube having an extension connecting with the discharge chamber and extending through the outer cap to constitute a liquid 110 discharge, and means for connecting the tubes of each pair to constitute opposite pole pieces of a circuit.

8. An electrical heater having nested tubular pole pieces and electrical connections 115 thereto, heads engaging the ends of said pole pieces to hold them together, and a supply and discharge pipe extending through both heads and within the nested tubes and provided with means for holding the heads upon 120 the tubular pole pieces and with supply and discharge openings, and a plug between said openings.

In testimony whereof, I have hereunto affixed my signature in the presence of two 125 witnesses.

OSCAR JOHNSON.
